UNITED STATES PATENT OFFICE.

HARVE D. ROSE AND ARCHIE MANTHE, OF WAMEGO, KANSAS.

HEADING AND ELEVATING MACHINE.

Application filed February 25, 1926. Serial No. 90,592.

Our invention relates to heading and elevating machines adapted for cutting the heads from the stocks of kaffir corn after the corn has been cut.

5 The object of our invention is to provide a simple portable mechanism that is handily conveyed through the field to the points of action hereinafter described.

10 A further object of our invention is to provide a mechanism adapted to carry its power actuating means.

15 A still further object of our invention is to provide a mechanism having attaching means to connect to the rear of a wagon bed as conveying means and simultaneously in proper position to discharge the severed heads centrally in the wagon bed.

20 A still further object of our invention is to provide a mechanism that will eliminate excess labor and cost of topping the kaffir corn, all of which is accomplished as hereinafter described.

Referring to the drawings:

Fig. I is a top view of the machine with 25 member 39 removed, the position thereof being shown by dotted lines.

Fig. II is a side view of the machine as attached to the rear end of a wagon bed.

30 Fig. III is an opposite side view from Fig. II.

The machine herein disclosed consists of a frame having a platform 1, vertical posts 2 and brace members 3 and 3', and a brace member 4 for the platform; the said frame being carried by wheels 5 positioned on each side thereof and rotatably mounted on an axle 6; the said axle being attached to the top side of the platform. Positioned on the platform is an internal combustion engine 7, and a gasoline tank 8. On one end of the crank shaft of the engine is a fly wheel 9; on the opposite end is a pulley 10 as means for transmitting power through the medium of a belt 11 to a pulley 12 which is rigidly connected to a shaft 13; said shaft being trunnioned in bearings 14 which are rigidly attached to the posts 2. On one end of said shaft is detachably positioned a circular-saw 15, and on the opposite end is a fly wheel 16. 40 On the outwardly extending end of the shaft is a pulley 17; the said pulley driving a belt 18 as a power transmitting element actuating a pulley 19 that is rigid on a shaft 20. On the opposite end of said shaft is a sprocket 21 functioning as the driving means for a feed chain 22; the said chain being horizontally

positioned and engaging on a sprocket 23. The object of the chain will hereinafter be more fully explained.

The said belt 18 engages on a pulley 24 which is the driving means for a roller actuating the travel of a conveying belt 25; said belt being the elevator for the kaffir corn heads from the cutting means to the wagon bed. As a tightening means for the belt 18, we have provided an idle pulley 26 mounted on the end of a lever 27; the said lever being fulcrumed on bolt 28 and vertically guided by a member 29 having rachets on the inside thereof to engage in the edge of 70 the lever, and caused to engage and disengage by springing the lever sideways for its upward and downward movement (the rachet not being shown).

Rigidly attached to the opposite side of 75 the frame from the pulleys is a table 30 having a groove 31 longitudinally positioned therein; the said groove adapted to receive the feed chain 22 in its rotation; the said chain being tensioned by a yoke having a 80 threaded portion 32 actuating the horizontal movement of the sprocket 23; (the said yoke not being shown in the sectional view of the table in Fig. 2).

Laterally extending and spaced along the 85 chain are fingers 33; said fingers functioning as conveying means to carry the bundles of kaffir corn towards the saw blade, and as the heads are severed they will drop on the conveying belt 26 approximately at a point A 90 as shown in Fig. 1. To prevent the heads from dropping downward over the lower end of the conveyor we have provided a baffle plate 34, the lower edge of which engages closely to the strips 35, transversely positioned and spaced along the said belt; the 95 said strips being of thickness sufficient to catch the shattered grain from the heads, conveying them to the wagon simultaneous with the heads.

The elevating means for the mechanism 100 consists of a forwardly extending chute having a bottom 36 and sides 37. On the inside of the sides is a cleat 38 lapping over the edges of the conveying belt which is preferably made of canvas. It will be understood 105 that the ends of the strips 35 travel closely to the sides of the cleat the object of this construction is to prevent the shattered grains from passing over the edges of the canvas. On the opposite side of the chute from the saw is an upwardly extending portion of the 110

side board as at B, and positioned on the top thereof is a board 39, the said members function as means to prevent the displacement of the heads while being cut. The member B functions as a bracing means attaching the frame and conveyor firmly together, while the opposite side is tied by means of the table 30 which is securely attached to the side board by an iron strap 40, and the opposite 10 end by a bracket 41; it being understood that the side to which the strap 40 is attached extends downward connecting to the posts 2.

Centrally positioned and rigidly attached to the side boards is a brace member 42 having a bar 43 attached to the apex thereof, and centrally positioned on said bar is a pin 44 adapted to engage in a perforation of an angle bar 45; last said bar being rigidly attached to an end gate 46 of the wagon bed 47; 20 note that the wheels of the wagon are not shown in connection with the bed, but it is understood that the wagon is the conveying means for the machine and means for conveying the severed heads to storage. On the 25 extreme outer end of the machine conveyor is a tensioning means 48 for the conveying belt, and should the belt be inclined to sag in its travel we have provided a semicircular plate 49 to prevent the cleat 35 from catching 30 on the bar 43 in their descent.

In Fig. III is shown a pivotally connected leg 50 functioning as a support when the machine is detached from the wagon bed, the 35 said leg is adapted to swing rearward to position on the side boards as shown by dotted lines.

To operate the machine is as follows:

When the field of kaffir corn is cut and shocked in the field, we take the machine and 40 attach it to the rear end of the wagon and drive to one of the shocks; the engine is then put in action actuating the saw and conveyors. The folder is then placed on the table with the heads projecting over the conveying belt, at 45 which time the fingers 33 draw the stocks in contact with the saw, severing the heads allowing them to drop on the conveyor as here-

tofore described. The fodder is then thrown aside, the cutting being quick in its operation. The shock of corn is soon headed, we then 50 move to the next shock which is done without the delay of detaching anchoring means and attaching means for such temporary transportation, and when the wagon bed is filled with the heads, we simply detach the pin 44 from its aperture and allow the machine to rest on the leg 50, and on return of the wagon 55 the pin is engaged and work proceeds for heading another load.

We do not confine the mechanism herein 60 disclosed to heading kaffir corn, as it may be used for cane or other headed grain.

Such modifications may be employed as lie within the scope of the appended claims.

Having thus described our invention, what 65 we claim as new and desire to secure by Letters Patent is:

1. In a heading and elevating machine, a frame carried by a pair of wheels, a slotted saw table positioned on the frame, an elevator chute attached to the frame, and having a standard pivotally connected to each side thereof as temporary supporting means therefor, a pivotal and removable connection comprising a bar and a pin centrally positioned and laterally extending from the bar, a brace member affixed to each side of the elevator as carrying means for the bar, said pin to be attached to the bed of a wagon as 70 conveying means for the machine. 75

2. In a heading and elevating machine, a frame, an engine, an elevator and shaft and saw positioned on the frame, the shaft and elevator actuated by the engine through the medium of a belt and a series of pulleys, a 80 table having a longitudinal slot extending therethrough, a conveyor chain passing through said slot, fingers on said chain for engaging the stalks of material to be cut, and moving against the saw, said elevator 85 to receive and convey the severed portions.

HARVE D. ROSE.
ARCHIE MANTHE.
